UNITED STATES PATENT OFFICE.

JOHN A. SHERMAN, OF WORCESTER, MASSACHUSETTS.

ENVELOP-MACHINE.

No. 843,707.

Specification of Letters Patent.

Patented Feb. 12, 1907.

Application filed January 11, 1906. Serial No. 295,533.

To all whom it may concern:

Be it known that I, JOHN A. SHERMAN, of Worcester, in the county of Worcester and State of Massachusetts, a citizen of the United States, have invented a new and useful Improvement in Envelop-Machines, of which the following is a full, clear, and exact description, reference being had to the accompanying drawings, forming a part of this specification, in explaining its nature.

My invention relates to an improvement in or rather an auxiliary attachment to machines for making envelopes by which such machines may make that type of envelop having an opening therein which is covered by some transparency or paper gummed or otherwise made to adhere to the envelop around the opening in the same.

It is the object of my invention to provide the envelop-machine with such means or to so adapt the same that without changing the usual mode and customary sequence of order of its operation it may make the above type of envelop.

My invention can best be seen and understood by reference to the drawings, in which—

Figure 1 represents in vertical section a portion of a machine containing my invention. Fig. 2 shows a section on the line 2 2 of Fig. 1. Fig. 3 shows a portion of the machine in plan, to which reference will herein-after be made. Fig. 4 shows a section on the line 4 4 of Fig. 3. Fig. 5 illustrates in plan a type of envelop which I desire to make, the same being shown unfolded. Fig. 6 shows in plan a slight modification in a portion of my improvement, to which reference will herein-after be made. Fig. 7 shows in detail a part thereof. Fig. 8 shows a section on the line 8 8 of Fig. 6. Fig. 9 shows in side elevation a modification in another portion of the device. Fig. 10 shows the same part in reverse side elevation.

While I desire it to be understood that my invention, which will now be explained, can be used with other types of envelop-making machines, it is especially adapted to be used with a type of machine substantially like that shown and described in my Letters Patent of the United States, No. 672,919, dated April 30, 1901. I have accordingly embodied in the present case various essential elements of the machine shown in said patent in

so far as they are pertinent to a proper understanding of the present case.

Referring to the drawings, A represents a portion of the frame of an envelop-making machine. Supported by this is the picker mechanism, which consists of a rigid support *a*, in which slides a vertical spindle *a'*, made to reciprocate in a manner well known to those skilled in the art. Hence no further reference need be made to its operating mechanism. At the lower end of the spindle *a'* are the pickers, which are attached to the spindle or connected therewith, so as to be operated by the same. I have shown two pickers *a²* *a³*, which are adapted to gum the flaps of the envelop-blank and raise the same to a position to be further manipulated, as customary in the operation of these machines. Supplementing these pickers and operating at the same time is an auxiliary picker *a⁴*, made oblong in shape, (see Fig. 2,) so as to enable it to gum that portion of the envelop-blank around the hole or opening cut in it, as before described.

The envelop-blanks B are stacked upon a supporting-table *a⁵*, placed below the pickers, and the pickers reach them in the operation of their reciprocation through slots cut in an interposed table *a⁶*, a supplementary slot *a⁷* being cut in the table to admit of the passage of the auxiliary picker *a⁴*.

Having thus far referred, in connection with the usual operating parts of the envelop-making machine, especially to the means of gumming that portion of the envelop around the hole or opening cut therein, reference will now be made to the mechanism by which the transparency or transparent paper is applied to the envelop for covering the hole or opening in it. The portion of the machine which I have utilized for the purpose above specified is the plunger mechanism used in connection with the creasing-table to force the blank down through it into the folding box. It will be unnecessary to explain how the blank reaches these parts from the pickers, the operation being so well known to those skilled in the art. Briefly referring to these parts, which are arranged upon the frame A, C represents the plunger upon the end of the plunger-rod *c*. D represents the creasing-table through the opening *d*, in which the plunger when operated is adapted to pass, and E represents the folding-box, against the

bottom or bed e of which the envelop-blank is adapted to be forced by the plunger and the flaps thereof afterward folded by the folders E' in the ordinary operation of the machine.

The plunger C may be of the usual construction except that it carries a box or casing C' . This box or casing forms practically a part of the plunger. In it are adapted to be contained a stack of transparencies B' , which in the operation of the plunger are destined to be applied to cover the hole or opening in the envelop-blank, as will hereinafter be explained. The form of plunger to which I shall first refer is of skeleton form and in one casting, like that shown in the drawings. (See Figs. 1 and 3.) It consists of heavy rectangularly-arranged side bars c' , c^2 , c^3 , and c^4 , having flat bottoms forming the face of the plunger. These bars form the main bearing portion of the plunger. Projecting inwardly from the side bar c' is a portion c^5 , on which is mounted a hub c^6 , located at about the middle of the plunger. Through the side of this hub there extends a set-screw c^7 . It is this hub and set-screw that furnish the means by which the plunger is detachably secured to the end of the plunger-rod, for the hub is adapted to receive the end of the plunger-rod and become attached thereto when the set-screw is turned up.

Referring now to the box or casing C' , this is located upon one side of the plunger out of the way of the plunger-rod and set in slightly from the outer edges of the bars forming the main portion of the plunger, as before described, so as not to interfere with the creasing-table as the plunger is operated. Moreover, the relative disposition of the box or casing is such as will bring it in that portion of the plunger directly above the hole or opening in the envelop-blank when located over the creasing-table in position to be operated upon by the plunger. The box is made larger than the opening in the envelop-blank or so as to contain transparencies of sufficient size to entirely cover said opening. The depth of the box or casing is such that it may contain a large number of transparencies. It is open at the bottom and extends down so far that the lower edges of the sides thereof will be substantially flush with the face of the plunger, thereby assisting in its operation and also enabling the bottom one of the blank transparencies contained in the casing to assume a position likewise substantially flush with the bottom or face of the plunger.

The blank transparencies are held within the box or casing by means of small clips or dividers c^8 , which extend inwardly from or under the bottom edges of the casing. These clips are arranged upon the ends of rods c^9 , which are secured or riveted to the sides of the casing near the top edges thereof. This

enables the rods to be spring-rods with a normal tendency to spring outward, carrying the clips on the ends thereof away from the opening in the bottom of the casing. These clips, however, are held in place by adjusting-screws c^{10} , which pass through the holding-rods and enter the sides of the casing. By adjusting these screws against the outward tension of the rods the clips c^8 upon the ends thereof may be adjusted to that point or position where they will be just sufficient to hold the transparencies in the casing, permitting, however, of the bottom one thereof being drawn off without disturbing the rest.

Certain of the clip-bearing rods pass through slots c^{11} , formed in the sides c^2 , c^3 , c^4 of the plunger. As above explained, the casing itself sets in slightly from the outer edges of these sides, and the clip-bearing rods secured to the sides of the casing are also set in by means of the said slots in order that when the plunger is operated these rods may not contact with the edge of the creasing-table.

Mention might also be made of a means for imparting a slight yielding pressure to the stack of transparencies in the box or casing to insure the positive feed thereof as the bottom one of the transparencies is successively drawn away, as will hereinafter be explained. This means consists of a presser-bar c^{12} , from which there extends upwardly a vertical rod c^{13} . On this rod is a spring c^{14} , the bottom end of which spring rests upon the presser-bar and against the upper end of which bears a collar c^{15} , which is loosely arranged upon the rod c^{13} . This collar forms the end of an angular rod c^{16} , socketed in the side of the casing to be vertically movable therein. By this means a constant yielding pressure is imparted to the transparencies in the casing, which also is self-adjusting, as the number of transparencies therein may vary. The means also is such that it may be easily removable when necessary to renew the stack of transparencies in the casing.

The operation of the parts is as follows: Understanding that that portion of the envelop-blank around the hole or opening therein has been gummed by means of the auxiliary picker a^4 , as before explained, and that the envelop-blank has passed to the creasing-table in the ordinary operation of the machine, the plunger then descending forces the blank through the creasing-table into the folding-box against the bottom or bed thereof. In this box the blank is held by the frictional or bearing contact of its flaps and also positively by means of the clips e' , forming the ends of the common goosenecks E^2 , adjustably secured to the frame of the machine, and outwardly under which clips the flaps of the envelop-blank are adapted to spring after being seated in the folding-box by the plunger. Now during the operation of the plunger the casing thereof containing the trans-

parcencies will have bearing over the hole or opening in the envelop-blank, for, as before explained, it is located to have such bearing. The effect is that the bottom one of the blank 5 transparencies will be applied to cover the hole or opening in the envelop-blank and will adhere to the gummed surface around the same, so that upon the return of the plunger the bottom one of the transparencies thus 10 retained will be pulled out from its retaining-clips or dividers and divided thereby away from the other transparencies in the box on the plunger and will be left permanently adhering to the envelop-blank, which 15 is then folded in the usual manner. It is accordingly to be observed that the transparency is applied to cover the hole or opening in the envelop-blank in the usual and continuous operation of the machine, all ele- 20 ments of the machine being employed to make this application without interfering in the least with their usual and normal sequence of operation. The changed type of envelop can accordingly be made as fast as 25 those of the common form or type.

In Figs. 6 to 10, inclusive, I have shown slight modifications of my invention in that the auxiliary picker a^4 and the box or casing carried by the plunger are so arranged and 30 adapted that their positions may be adjustably changed. This is a desirable factor, inasmuch as the location of the hole or opening in different styles of envelopes may vary, and it is to meet this variation in the position of 35 the hole or opening in the envelope that the picker and box or casing are preferably made adjustable parts.

Referring first to the box or casing on the plunger, I have shown in Fig. 6 a plunger F 40 made of rectangularly-arranged side bars f^1 f^2 f^3 , substantially like the plunger before described. Fastening into opposite ones (f^1 f^2) of these bars of the plunger is a yoke f^4 , bearing a hub f^5 , into which the plunger-rod is 45 adapted to extend and be secured by a set-screw f^6 . This arrangement leaves ample room for the adjustment within the plunger of the box or casing C for containing the transparencies. I provide for the adjust- 50 ment of the box or casing by attaching to opposite sides thereof by means of bolts f^7 the respective angle-pieces f^8 f^9 , which are secured to the adjacent side bars f^1 f^3 of the plunger by means of bolts or screws f^{10} . Then 55 by means of a series of slots cut in these angle-pieces through which these screws or bolts extend not only may the lateral or longitudinal adjustment of the box be pro- 60 vided, but its vertical adjustment also. Of course this arrangement for securing the ad- 65 justment of the box is simply tentative and may be changed without departing from the spirit of this phase of my invention.

Referring now, in Figs. 9 and 10, to the 65 mode of adjusting the auxiliary picker a^4 ,

it is to be noted that the picker is provided with a bent arm a^8 , which extends through a wide slot a^9 , formed in an attachment a^{10} , secured to a portion of the frame supporting the picker mechanism. The arm of the 70 picker is adapted to be laterally and longitudinally adjustable in this slot and is held therein at various points of adjusted position by means of adjustable screws a^{11} , which extend through the sides of the attachment 75 and engage with said arm, the screw then being held by means of locking-nuts a^{12} .

Having thus fully described my invention, I claim and desire to secure by Letters Patent of the United States—

1. In a machine for making envelopes, the picker mechanism and combined therewith, means for gumming an envelop-blank around a hole or opening therein, the plunger mechanism to which the envelopes are fed from 85 said picker mechanism in the operation of the machine, and combined with said plunger mechanism, means whereby a transparency or paper may be automatically applied to said gummed portion of the blank to cover 90 the hole or opening therein.

2. In a machine for making envelopes, the picker mechanism, a picker forming a part thereof and operable simultaneously therewith, which picker is adapted to gum that 95 portion of an envelop-blank around a hole or opening therein, the plunger mechanism, a base against which the plunger is adapted to operate, and carried by said plunger and operable simultaneously therewith, means whereby transparencies or paper may be applied to said gummed portion of the envelop-blank to cover the said hole or opening therein.

3. In a machine for making envelopes, the 105 picker mechanism and reciprocating simultaneously therewith means for gumming that portion of an envelop-blank around a hole or opening therein, the plunger mechanism to which said gummed blanks are fed in the operation of the machine, the plunger carrying a stack of transparencies adapted to be successively applied to said gummed portion of the envelop-blank to cover the hole or opening 110 therein, a base against which the plunger is 115 adapted to reciprocate for applying said transparencies to the envelop-blank, and means for retaining said transparencies whereby they may be independently and successively drawn away from the plunger after 120 being applied to the envelop-blank.

4. In a machine for making envelopes, the picker mechanism, a picker forming a part thereof and operable simultaneously therewith, which picker is adapted to gum that portion of the envelop-blank around a hole or opening therein, the plunger mechanism, a creasing-table and folding-box to which parts 125 said gummed envelop-blank is carried in the ordinary operation of the machine, a box or 130

casing carried by said plunger and operatable simultaneously therewith, said box being open at the bottom, and clips for holding said blank transparencies or paper in said 5 box of the plunger, whereby a transparency or paper may be applied to said gummed portion of the envelop-blank to cover the hole or opening therein substantially as described.

- 10 5. In an envelop-machine, the plunger mechanism and in combination therewith, a box carried by said plunger and operatable therewith, a base against which the plunger is adapted to reciprocate, said box of the 15 plunger being open at the bottom and adapted to contain a stack of transparencies or paper destined to be applied through the open bottom of said box to a gummed envelop-blank for covering a hole or opening in said 20 blank, and clips for retaining said stack of transparencies or paper within the box of the plunger, whereby a transparency or paper may be extracted from the stack therein after 25 being applied to said gummed blank upon the reciprocation of the plunger against said base.

6. In an envelop-making machine, the picker mechanism and in combination therewith, adjustable means for gumming an envelop-blank around a hole or opening therein, plunger mechanism to which the envelop is fed in the operation of the machine and in combination therewith, adjustable means whereby a transparency or paper may be automatically applied to the gummed portion 30 of the envelop-blank to cover the hole or opening therein.

7. In a machine for making envelops, the picker mechanism, a picker forming a part 35 thereof and operatable simultaneously therewith, which picker is adapted to gum that

portion of an envelop-blank around a hole or opening therein, means whereby the lateral adjustment of said picker may be effected, the plunger mechanism, a base against which the 45 plunger is adapted to operate, a box or casing carried by said plunger, said box carried by the plunger being open at the bottom and adapted to contain a stack of transparencies or paper destined to be applied through the 50 open bottom of said box to the gummed envelop-blank for covering the hole or opening in said blank, means for retaining said stack of transparencies or paper within the box of said plunger whereby a transparency or 55 paper may be extracted from the stack therein upon the reciprocation of said plunger against said base, and means whereby said box may be adjustably mounted upon said plunger.

8. In an envelop-making machine, the plunger mechanism having a plunger consisting of rectangularly-arranged side bars with a yoke connecting the same to the plunger-rod, a box or casing within said side bars, 65 means for adjustably connecting the same therewith, whereby said box or casing may be adjusted to assume different positions on said plunger, which box or casing is open at the bottom and adapted to contain a stack of 70 transparencies or paper destined to be applied through the open bottom of said box to a gummed envelop-blank for covering a hole or opening in said blank, and means for retaining said transparencies or paper within 75 said box or casing whereby they may be independently and successively applied as aforesaid.

JOHN A. SHERMAN.
